TEXTILE APPARATUS

Frank H. Kaufmann, Elkins Park, Pa., assignor
to Steel Heddle Manufacturing Company, Philadelphia, Pa., a corporation of Pennsylvania

Application August 25, 1937, Serial No. 160,767

7 Claims. (Cl. 28—54)

This invention relates to textile apparatus, and it relates more particularly to improved means for spacing metallic strips, such as the dents of combs and reeds used in various textile operations; and it is also applicable in some instances for maintaining the separation of flat steel heddles used in loom harness.

Heretofore various forms of spacing devices have been used for spacing or separating the dents of combs and reeds used in textile operations, and for maintaining a minimum amount of separation of flat steel heddles used in loom harness. However, none of these devices have proved entirely satisfactory under all conditions.

15 The principal object of the present invention is to provide means for maintaining the separation or spacing of metallic strips used in textile apparatus, such as the dents of combs and reeds, and the heddles of loom harness, which will be relatively inexpensive yet entirely efficient for the intended purpose.

A further object of the invention is to provide means for maintaining the separation or spacing of such metallic strips, in the use of which there will be no tendency to bend or flex the metallic strips adjacent the separating device.

25 A further object of the invention is to provide separating or spacing means for such metallic strips, in the use of which there will be no torsional strains set up which would tend to twist the strips out of their proper parallel planes.

30 A further object of the invention is to provide separating or spacing means for such metallic strips which may be readily incorporated in said strips, at the time of their manufacture, by ordinary punching and forming operations.

The nature and characteristic features of the invention will be more readily understood from the following description taken in connection with the accompanying drawing forming part hereof, in which:

35 Figure 1 is an elevational view of a comb or reed, adaptable for use in warp preparation, embodying the main features of the present invention;

40 Fig. 2 is a face view of one of the dents thereof removed from the frame;

45 Fig. 3 is a similar view of another of said dents;

50 Fig. 4 is a horizontal section, enlarged, taken on the line 4—4 of Fig. 1;

55 Fig. 5 is a perspective view of a portion of one of the dents shown in Figs. 1 and 2;

Fig. 6 is an elevational view illustrating a

modified form of the invention, as there shown being applied to the upper end portions of a group of heddles of a loom harness frame, the same being mounted on one of the usual heddle supporting rods; and

Fig. 7 is a horizontal section, enlarged, taken on the line 7—7 of Fig. 6.

It will, of course, be understood that the drawing and description herein contained are illustrative merely, and that various changes and modifications may be made in the structure disclosed without departing from the spirit of the invention.

Referring to the drawing, with particular relation to Figs. 1 to 5, there is there shown one form or construction of a reed or comb 10 used in various textile operations, as for example, for guiding the warp to or from a slasher. Said device consists of a suitable frame 11, having side struts 12, and disposed between said side struts 12, spacing dents 13 and plain dents 14 are mounted in alternate relationship, said dents being rigidly secured at their lower ends in the frame 10 in the usual manner of construction of soldered reeds.

As there shown, each of the dents 13 and 14 comprises a thin flat strip of metal, the dents 13 being each provided, adjacent the free ends thereof, with a spacing device of peculiar formation. Said spacing device is formed by splitting the metal of the dent at a place where said spacing device is to be located, thereby to provide three longitudinal strips. The central strip 15 is pressed and formed out of the main plane of the dent 13, a distance corresponding to the amount of separation required. Likewise, the side strips 16 are also pressed and formed out of the main plane of the dent 13, but in a direction opposite to that of the central strip 15.

The dents are mounted in the frame in alternate relationship, that is to say, a spacing dent 13 is in each instance disposed between a pair of plain dents 14. It will be noted that by this arrangement, with reference particularly to Fig. 4 of the drawing, each of the side strips 16 of the spacing device will bear against the face of one of the adjacent dents 14 in symmetrical relationship, whereas the central strip 15 of the spacing device will bear against the central portion of the face of the other adjacent plain dent 14. By this arrangement, there will be no torsional strains set up which would tend to twist any of the dents out of its normal and proper plane.

It should also be noted that the strips 15 and 16

16, constituting the spacing device, which are provided on the dent 13, will have flat portions of sufficient longitudinal extent and disposed in planes parallel to the main plane of the dent, 5 so that there will be no bending strains set up in the dents which would tend to distort or flex the same adjacent the spacing device.

It will, of course, be readily understood that the invention is equally applicable for the spacing of metallic strips in other textile apparatus, whether the same be mounted rigidly in the 10 frame, as is common in certain reeds and combs, or whether the same be mounted in expansion types of reeds and combs, or for the maintaining 15 of a minimum spacing of the heddles used in loom harness.

In Figs. 6 and 7 of the drawing, there is shown a modified form of the invention as applied to the heddles of a loom harness frame. In this 20 instance, all of the heddles 13^a are provided with a spacing device adjacent the place where they are mounted on the heddle rod 18, and the plain unformed members are omitted. However, each alternate heddle is turned with respect to the 25 others so that the longitudinal strips 16 at the sides of a particular heddle will bear against the longitudinal strip 16 at the sides of an adjacent heddle, and likewise the central longitudinal strip 15 of a particular heddle will bear against 30 the central longitudinal strip 15 of the outer next adjacent heddle. Also in this form, in which the intermediate plain members are omitted, the spacing strips 15 and 16 will be pressed 35 out of the main plane of the heddle a distance corresponding to but one-half of the amount of the minimum separation desired.

It will, of course, be apparent that the form of the invention shown in Figs. 6 and 7 of the drawing is readily adaptable for use in various forms 40 of textile combs and reeds, and that likewise, the form of the invention shown in Figs. 1 to 5 of the drawing is adaptable for use in connection with certain forms of heddles used in loom harness.

I claim:

1. In textile apparatus including a plurality of thin flat metallic members disposed in spaced relationship, the means for spacing said members comprising the provision, at one portion of 50 each of certain of said members, of a central strip offset from the main plane of the member on one face thereof, and two side strips offset from the main plane of the member on the other face thereof.

2. In textile apparatus including a plurality of thin flat metallic members disposed in spaced relationship, the means for spacing said members comprising the provision, at one portion of each of certain of said members, of a central strip offset from the main plane of the member on one face thereof, and two side strips offset from the main plane of the member on the other face thereof, the main portions of said strips being flat and disposed in planes parallel to the main plane of the 65 member.

3. In textile apparatus including a plurality of thin flat metallic members disposed in spaced relationship, the means for spacing said members comprising the provision, at one portion of each alternate member, of a central strip offset from the main plane of the member on one face thereof, and two side strips offset from the main plane of the member on the other face thereof, the main portions of said strips being flat and disposed in planes parallel to the main plane of 10 the member. 5

4. In textile apparatus including a plurality of thin flat metallic members disposed in spaced relationship, the means for spacing said members comprising the provision, at one portion of each alternate member, of a central strip offset from the main plane of the member on one face thereof, and two side strips offset from the main plane of the member on the other face thereof, the main portions of said strips being flat and 15 disposed in planes parallel to the main plane of the member, and the other alternate members each being plain at that portion thereof which is adjacent the offset strips of the adjacent alternate members. 20

5. In textile apparatus including a plurality of thin flat metallic members, means for spacing said members comprising the provision in certain of said members, at one portion thereof, of at least three longitudinally extending strips offset from 25 the main plane of the member, at least two of said offset strips being disposed on one face of the member, and at least one of said strips being disposed on the other face thereof. 30

6. In textile apparatus including a plurality of thin flat metallic members, means for spacing said members comprising the provision in certain of said members, at one portion thereof, of at least three longitudinally extending strips offset from the main plane of the member, at least 40 two of said offset strips being disposed on one face of the member, and at least one of said strips being disposed on the other face thereof, the main portions of said strips being flat and disposed in planes parallel to the main plane of 45 the member. 35

7. In textile apparatus including a plurality of thin flat metallic members, means for spacing said members comprising the provision in certain of said members, at one portion thereof, of at 50 least three longitudinally extending strips offset from the main plane of the member, at least two of said offset strips being disposed on one face of the member, and at least one of said strips being disposed on the other face thereof, 55 the main portions of said strips being flat and disposed in planes parallel to the main plane of the member, and said members with said offset strips being disposed in alternate relationship with other members which are plain at that portion thereof which is adjacent the offset strips of the first mentioned members. 60
